US0D1103916S

(12) **United States Design Patent** (10) **Patent No.:** **US D1,103,916 S**
(45) **Date of Patent:** **** Dec. 2, 2025**

(54) **INVERTER-CHARGER**

(71) Applicant: **Shenzhen Sunlite Technology Co., Ltd.**, Shenzhen (CN)

(72) Inventor: **Xiaoliang Han**, Shenzhen (CN)

(**) Term: **15 Years**

(21) Appl. No.: **29/891,989**

(22) Filed: **May 12, 2023**

(30) **Foreign Application Priority Data**

Apr. 13, 2023 (CN) 202330200695.8

(51) **LOC (15) Cl.** **13-02**

(52) **U.S. Cl.**

USPC **D13/107**

(58) **Field of Classification Search**

USPC D13/103, 104, 107, 108, 109, 119, 155,

Assistant Examiner — Devin Kelly

(57) **CLAIM**

The ornamental design for an inverter-charger, as shown and described.

DESCRIPTION

FIG. 1 is a first perspective view of an inverter-charger showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the inverter-charger that form no part of the claimed design.

1 Claim, 8 Drawing Sheets
